UNITED STATES PATENT OFFICE

FREDERICK HAGGER HEADLEY, OF NORTHFIELD, BIRMINGHAM, ENGLAND; ANNIE BOWDEN HEADLEY, EXECUTRIX OF SAID FREDERICK HAGGER HEADLEY, DECEASED, ASSIGNOR TO THE TAN SAD CHAIR COMPANY (1931) LIMITED, OF BIRMINGHAM, ENGLAND, A BRITISH COMPANY

CHAIR, SEAT AND THE LIKE

Application filed November 3, 1928, Serial No. 317,045, and in Great Britain February 20, 1928.

The present invention has relation to chairs, seats or the like, more particularly the back-rests or back supports thereof. Back-rests or supports for chairs, seats or the like have previously been proposed of an adjustable character both with regard to inclination and elevation.

The present invention has for its object to provide back-rest or support mechanism having a simple and unified form of adjustment mechanism which will permit of a particularly speedy and secure setting of the back-rest or support proper in the desired position.

In order that this invention may be clearly understood and readily carried into practice, reference may be had to the appended explanatory sheet of drawings, upon which:—

Figure 1 is a perspective view of a seat incorporating adjustable clamping mechanism for the back-rest constructed according to the present invention.

Figure 2 is a sectional plan view taken horizontally through the clamping mechanism shown in Figure 1.

Figure 3 is a transverse sectional elevation taken on the line 3—3 of Figure 2.

Figure 4 is a sectional view corresponding to that shown in Figure 2 only of a modification of the present invention.

Figure 5 is a transverse sectional elevation taken on the line 5—5 of Figure 4.

In that embodiment of the present invention illustrated in Figures 1, 2 and 3, the seat *a* (Figure 1) is provided on its underside with a frame *b* (Figure 2) having rearwardly extending, laterally spaced arms *c* and *d* respectively. Attached to the arm *c* is an annular radially serrated element *e* which is adapted to co-operate with an oblong serrated element *f* having a channel or slide-way *f1* and a boss *f2* rotatable in a blind aperture *c1* in the arm *c*. *g* is the upright post which at its upper extremity carries the back-rest *h*, which arm in the form illustrated is of hollow square section tubing reinforced with a wooden liner. This post *g* is adapted to slide in the channel or slide-way *f1* and is operable by means of a hand-screw member *i* operating in a tapped aperture in the arm *d*. *j* is a coiled compression spring interposed

between the serrated plate *e* and the complementary plate *f*.

In operation, in order to adjust the rearward or forward setting and elevation of the back, the hand-screw *i* is unscrewed and the post *g* seized by the hand. The arm can then be slid vertically in its channel *f1* and it can also be rotated on account of the serrated faces being disengaged by the spring *j*. That is to say, the arm and back are capable of a universal movement in a fixed plane. When the desired adjustment has been obtained, the hand-screw *i* is tightened to effectively secure the parts in their new position of adjustment.

It will be appreciated therefore that by the manipulation of a single hand-screw, a universal adjustment of the back may be obtained, that is to say, an adjustment both with respect to inclination of the supporting post obtaining forward and rearward movement of the back-rest or support, and the vertical adjustment of the said post obtaining a corresponding movement of the said back-rest or support.

The post *g* may carry at its upper extremity a forked member *g1* wherein the back-rest *h* is adapted to swivel or pivot as at *g2* on a horizontal axis for small automatic adjustment purposes.

In that modification of the invention illustrated in Figures 4 and 5, the part *b* is attached to the underside of the seat *a* and is provided as hereinbefore with the arms *c*, *d*. The arm *c* has attached thereto a plate *e* having a plurality of radial serrations, and also carries a bolt *k* which is keyed as at *k1* against rotation. The lower part of the supporting post *g* in this modification is slotted as at *g3*, see particularly Figure 5, to accommodate the bolt *k*, and said post *g* is itself accommodated in a channel *f2* in a serrated plate member *f* mounted upon the bolt *k* which is complementary to the plate *e* secured to the arm *c*. *j* is a coiled compression spring tending to separate the complementary serrated plates *e* and *f*. *l* is a distance piece operating in an aperture in the arm *d* between the post *g* and the hand-screw member *m*.

In the operation of this modification, in order to adjust the back the handscrew *m* is unscrewed, and the post *g* being seized by the hand can be slidily adjusted in the channel *f2*, and/or rotated with the member *f* inasmuch as the serrated faces are disengaged by the spring *j*. The parts are secured in their position of adjustment (Figure 4) by tightening the hand-screw *m*.

10 *n* is a peg or projection on the stationary plate *e* which may be provided for the purpose of limiting the rearward pivotal movement of the post *g* by contacting the complementary plate *f* and thereby preventing the 15 back-rest from falling rearwardly towards the ground.

I claim as my invention:

1. A chair embodying therein a member having laterally spaced arms, one of which 20 has radial serrations thereon, a device having a guide channel on one face and radial serrations on the other face disposed between said arms, means providing a pivotal connection for said device with respect to said 25 arms, a back rest supporting post longitudinally adjustable in said guide channel and means arranged axially of said device and disposed in part upon the other side of the other arm for clamping said post to said device and for clamping said device against 30 said first mentioned arm.

2. A chair embodying therein a member having laterally spaced arms, one of which has radial serrations thereon, a device having a guide channel on one face and radial serrations on the other face disposed between 35 said arms, means providing a pivotal connection for said device with respect to said arms, a back rest supporting post longitudinally 40 adjustable in said guide channel, means arranged axially of said device and disposed in part upon the other side of the other arm for clamping said post to said device and for clamping said device to said first mentioned 45 arm with the serrations thereon and a spring interposed between said first mentioned arm and said device.

3. A chair embodying therein a seat, a pair of laterally spaced arms projecting to 50 the rear of said seat, a device associated with one of said arms and rotative with respect thereto, said device and arm having radial interengaging parts thereon, a seat post longitudinally 55 adjustable mounted on said device and a rotatable member threaded in the other arm for engagement with said post to clamp said post to said device and to hold said device against the first mentioned arm and against rotation with respect thereto.

60 4. A chair embodying therein a seat, a pair of laterally spaced arms projecting to the rear of said seat, a device associated with one of said arms and rotative with respect thereto, said device and arm having radial 65 interengaging parts thereon, a seat post

longitudinally adjustably mounted on said device and means between said first mentioned arm and said device normally urging said device away from said arm and a rotatable member threaded in the other arm 70 for engagement with said post against the action of said last mentioned means to clamp said post to said device and to hold the said device against the first mentioned arm and against rotation with respect thereto. 75

5. A chair embodying therein a seat, a pair of laterally spaced arms projecting to the rear of said seat, a device associated with one of said arms and rotative with respect thereto, said device and arm having radial interengaging parts thereon, a seat post longitudinally 80 adjustable mounted on said device and a screw threaded in the other arm and operable to engage the post to hold it in said device and to hold said device against said first mentioned arm.

6. A chair embodying therein a member having laterally spaced arms, a device positioned between said arms and having a guide channel, means providing a pivotal connection for said devices with respect to one of said arms, a back rest post disposed in said guide channel for longitudinal adjustment, said one of said arms and said device having interengaging parts for determining the angular position of said device relative to said one of said arms and means disposed in the other of said arms coincident with the axis of said device for clamping the back rest post in said channel and for clamping 100 said device to said one of said arms.

In witness whereof I have hereunto set my hand.

FREDERICK MAGGER HEADLEY.
